MULTIFACED DOLL

Wanda L. Paul, New York, N. Y., assignor of one-half to Carl J. Anderson, New York, N. Y.

Application January 9, 1947, Serial No. 720,988

8 Claims. (Cl. 46—153)

1

This invention relates to multifaced dolls and more particularly to apparatus and devices for selectively maintaining the position of doll heads in a fixed position.

One object of the invention is to provide an improved device or apparatus of this kind which provides a multifaced head rotatable about a horizontal axis and in which the head may be locked in a definite position.

Other objects of the invention are to provide an improved device of this kind in which the head is selectively automatically locked in position for each of the faces as the head is rotated.

Additional objects of the invention are to effect simplicity and efficiency in such methods and apparatus and to provide an extremely simple device or apparatus of this kind which is economical, durable, and reliable in operation, and economical to manufacture.

Still other objects of the invention will appear as the description proceeds; and while herein details of the invention are described in the specification and some of the claims, the invention as described in the broader claims is not limited to these and many and various changes may be made without departing from the scope of the invention as claimed in the broader claims.

The inventive features for the accomplishment of these and other objects are shown herein in connection with a multifaced doll which briefly stated, includes a doll body having a head mounting U member in the normal neck region thereof and a telescoping triangular rod bearingly mounted therein. A multifaced head is substantially fast thereon and detent means are provided to automatically lock the head in one of several face positions.

In the accompanying drawing showing, by way of example, one of many possible embodiments of the invention,

Fig. 1 is a fragmental front view of the doll body and head mounted thereon;

Fig. 2 is a fragmental side view of the invention as shown in Fig. 1;

Fig. 3 is a side view showing details of the head;

Fig. 4 is a vertical transverse sectional view of the head and mounting means; and

Fig. 5 is a fragmental side view of mounting of Fig. 4 and showing details of the triangular rod on detent means.

My doll comprises a body 10 except for neck and head; over which a pair of spaced metal straps are mounted fast in the neck region of the body and extending toward the back and chest of the

2

body. A strong head mounting U-member strip generally designated as 12 has the yoke thereof mounted fast on said straps as by rivets 14, the yoke being near said neck region, and the arms 15 and 15' of said member projecting upwardly and substantially in the plane of the shoulders of the body. The end portions of the yoke arms are provided with horizontally axially alined bearing openings 16 and 18, the marginal portions around the openings being dished inwardly as at 19 and 20.

A telescoping rod 21 of equilateral triangular cross section has journals at each end thereof disposed in said openings. One journal may be in the form of a long stud 22 and the other a short headed screw 24. Said rod 21 comprises a shaft 25 of wood, plastic, metal or other similar material of triangular cross section and on which a capped metal triangular sleeve 26 is slidably received on the inner end portion of the shaft. A compressed spring 28 between the inner end of the shaft in the inner face of the cap of the sleeve normally assures the rod to be in extended form. The journals 22 and 24 project from the outer ends of the sleeve and shaft respectively, all in axial alinement. A detent stop 29 projects inwardly from the arm 15 near the sleeve and is adapted to engage the lateral faces of the sleeve substantially on the center lines in the sleeve faces. The stop is in the form of an inwardly turned tongue integral with the U member strip and partially cut from the marginal portion of the opening 16 therein.

A hollow substantially spherical head 30 having triangular openings 31 in the ear portions thereof is mounted on said rod non-rotative with respect thereto. The head is provided with three faces 32a, 32b, and 32c each covering horizontally a third of the spherical surface. When the journal 22 nearest the detent stop 29 is pressed inwardly to telescope the rod, the outer end of the sleeve will clear the stop so that the head and rod may be rotated to bring another head face into normal position. On release of the journal if one of the faces is in normal position the rod will become extended and the stop will engage the corresponding face of the sleeve and hold the head in a fixed position.

If one of the head faces is not in normal position the head will rotate in either direction for the end of the stop will bear against the smooth outer end of the sleeve, but when a thin portion of the rod comes in line with the stop the rod extends and is held against further turning. The head 30 may be made in any manner

known to the art. It may be advisable to make the ear portion adjacent the sleeve of more durable material as shown at 34. If that portion is made separate the opening into which it is fitted will enable the fitting of eyes from within the head. The portion 34 may be glued or cemented to the remainder of the head.

Of course the journals 22 and 24 may be of any suitable form. The headed screw is preferable for the non-sliding end since it may be short and yet must not slip from its bearing.

The invention claimed is:

1. A multifaced doll comprising a body and head mounting means thereon including upwardly projecting yoke arms provided with bearing openings therein; a telescoping rod of equilateral triangular cross section having journals secured fast on each end thereof and disposed in said openings; and detent stop means projecting inwardly from one of the arms and adapted to engage one of the lateral faces of the rod.

2. A multifaced doll comprising a telescoping rod of equilateral triangular cross section having journals at each end thereof; said rod comprising a shaft of equilateral triangular cross section; a capped metal triangular sleeve slidably received on the inner end portion of the shaft and a compressed spring between the inner end of the shaft and the inner face of the cap of the sleeve, said journals projecting from the outer ends of the sleeve and shaft respectively, all in axial alignment; and a three-faced head mounted on said rod and non-rotative with respect thereto, center lines of the head faces being in a plane perpendicular to the rod and the faces equally distributed over the entire surface of the head.

3. A multifaced doll comprising a body; a sturdy head mounting U-member strip having the yoke thereof mounted fast on said body, the yoke being at the neck region, and the arms of said member projecting upwardly; the end portions of the yoke arms being provided with horizontally axially aligned bearing openings; a telescoping rod of equilateral triangular cross section having journals at each end thereof disposed in said openings; a detent stop projecting inwardly from one of the arms and adapted to engage one of the lateral faces of the rod substantially at points nearest the axis of the rod; said stop being an inwardly turned tongue integral with the U-member strip and formed from the marginal portion of the opening therein; and a three-faced head rigidly mounted on the rod and having the three faces equally distributed over the entire surface of the head about the axis thereof.

4. A multi-faced doll comprising a body; a sturdy head mounting U-member strip having the yoke thereof mounted fast on said body, the yoke being substantially at the neck region, and the arms of said member projecting upwardly; the end portions of the yoke arms being provided with horizontally axially aligned bearing openings; a telescoping rod of equilateral triangular cross section having journals at each end thereof disposed in said openings; said rod comprising a wooden shaft of triangular cross section, a capped metal triangular sleeve slidably received on the inner end portion of the shaft, and a compressed spring between the inner end of the shaft and the inner face of the cap of the sleeve, said journals projecting from the outer ends of the sleeve and shaft respectively, all in axial alignment; a detent stop projecting inwardly from one of the arms and adapted to engage one of the lateral

faces of the sleeve substantially on the longitudinal center line in such face, the center lines of said lateral faces being nearest the axis of the rod; and a head mounted on said rod and non-rotative with respect thereto.

5. A multifaced doll comprising a body and head-mounting means thereon including a U member having upwardly projecting yoke arms provided with horizontally axially aligned bearing openings therein; a telescoping rod of equilateral triangular cross section having journals at each end thereof disposed in said openings, a detent stop projecting inwardly from one of the arms and adapted to engage the lateral faces of the rod substantially at points nearest the axis of the rod; and a hollow substantially spherical head having triangular openings in the ear portions thereof and mounted on said rod and non-rotative with respect thereto; said head being provided with three faces each covering a third of the spherical surface, whereby the journal nearest the detent stop may be pressed inwardly to telescope the rod causing the end thereof to clear the stop so that the head and rod may be rotated to bring another head face into normal position, and upon release of the journal the rod will be extended and the stop will engage another face of the rod and hold the head in a fixed position.

6. A multifaced doll comprising a body; a sturdy upwardly projecting U-member strip mounted fast on said body, the end portions of the U-member arms being provided with horizontally axially aligned bearing openings, the marginal portions around the openings being dished inwardly; a telescoping rod comprising a wooden shaft of triangular cross section, a capped metal triangular sleeve slidably received on the inner end portion of the shaft and a compressed spring between the inner end of the shaft and the inner face of the cap of the sleeve, journals projecting from the outer side of the sleeve and shaft respectively, all in axial alignment and in said bearing openings; a detent stop projecting inwardly from one of the arms and adapted to engage one at a time the lateral faces of the sleeve of the rod, said stop being an inwardly turned tongue integral with the U-member strip and formed from the marginal portion of the opening therein; and a substantially spherical head mounted on said rod and non-rotative with respect thereto.

7. A multi-faced doll comprising a body and head mounting member thereon including upwardly projecting yoke arms provided with bearing openings therein; an axle member having journals on each end thereof and disposed in said openings and passing therethrough; one of the journals being movable relative to the adjacent yoke arm in a direction axial of the axle member, said axle member having radial projections near the last mentioned journal, a detent stop projecting axially inwardly from the arm adjacent the projections and adapted to engage same.

8. A multi-faced doll comprising a body and head mounting member thereon including upwardly projecting yoke arms provided with bearing openings therein; an axle member having journals on each end thereof and disposed in said openings and passing therethrough; one of the journals being movable relative to the adjacent yoke arm in a direction axial of the axle member, a head fast on at least part of the axle member, said axle member having radial projections near the last mentioned journal, a detent stop projecting axially inwardly from the arm ad-

5

jacent the projections and adapted to engage same; whereby pressing on the last mentioned journal in an axial direction will cause the projections to clear the stop and the head may be rotated.
